UNITED STATES PATENT OFFICE.

MATIAS BALSEERA RODRIGUEZ, OF LONDON, ENGLAND.

TELEGRAPHIC PRINTING APPARATUS.

1,275,474.

Specification of Letters Patent.

Patented Aug. 13, 1918.

Application filed March 20, 1916. Serial No. 85,463.

To all whom it may concern:

Be it known that I, MATIAS BALSEERA RODRIGUEZ, a subject of the King of Spain, residing at 33 Brunswick Square, London, 5 W. C., England, have invented a certain new and useful Telegraphic Printing Apparatus, of which the following is a specification.

This invention relates to telegraphic apparatus by which transmitted messages are recorded by printing mechanism incorporated in the receiving apparatus and has for its object to provide an improved apparatus which is simple in design, inexpensive 15 of manufacture and efficient in operation.

According to the invention an apparatus is provided in which the oscillation of a single lever under the control of an electromagnet serves to effect the printing impression, to effect the forward and intermittent feed of the strip material upon which the impression is made and also to effect the discharge of the line conductor after the transmission of each message, sign or letter.

According to the invention, also, the movement of the operating lever to effect an impression is made under the action of a uniform and continuously applied force which, in the operative position of the lever, 25 is overcome by the control magnet.

The apparatus has a type wheel which is constantly rotated and according to the invention, the return movement or rebound of the impression member from the type wheel 35 after an impression has been made is assisted by continuously applied force of adjustable value, which serves also for the regulation of the pressure with which the impression member is projected against the type 40 wheel for the impression.

Means are provided whereby an impression of the letter or sign transmitted is effected simultaneously at the transmitting and receiving stations, notwithstanding the 45 retardation due to electro-static charging and the self-induction of the line, so that verification and correction may be readily effected.

The constantly rotated type wheels of the 50 transmitting and receiving apparatus, which are quite independent the one of the other, are automatically synchronized, if necessary

once in every revolution. While the principle of operation of the mechanism provided for this purpose is not novel, the application 55 to automatic synchronization has not before been proposed.

A particular construction of the apparatus according to the invention, together with the electrical circuits therefor, is represented in the accompanying diagrammatic drawings in which:

Figure 1 is a transverse sectional elevation of the apparatus, taken along the type-wheel shaft, which also carries the selector arm, and showing the synchronizing mechanism which is advantageously provided on at least one of the two apparatus employed in connection with the line conductor;

Fig. 2 is a view in elevation of the distributor which coöperates with the selector arm, and showing the construction of distributor employed in the case of the apparatus whence the synchronizing current is directed;

Fig. 3 is an elevation of the apparatus showing the lever by which the operations of the apparatus are effected, the electromagnet by which it is controlled and the type wheel; and

Fig. 4 is a diagram of the connections of the apparatus provided with the synchronizing mechanism.

In the apparatus provided according to the invention and illustrated in the drawings, front and rear frame members, 7 and 5, respectively, are provided and a type wheel shaft 2 is carried in suitable bearings formed in the said frame members with its extremities 6 and 4 extending outwardly 90 from the respective frame plates. A driving member 1, receiving motion from a suitable prime mover giving a uniform rate of speed, is loosely mounted upon the shaft 2 adjacent a collar or flange rigidly mounted 95 upon the shaft, against which collar or flange 1^a it is pressed by means of a spring 3 so that it becomes frictionally engaged with the shaft for the purpose of imparting motion thereto unless resistance is imposed upon the shaft. The driving member

for receiving and transmitting rotary motion from a prime mover, such as an electric motor, may conveniently be a worm wheel, 100

the teeth 1^b of which are partially indicated in dotted lines in Fig. 2 in engagement with a worm 1^c.

Upon the outer face of the frame member 5 is fixedly mounted the element 9 which is termed the distributor and which co-operates with the selector arm 8 carried by the extremity 4 of the shaft 2. Upon the opposite extremity 6 of the shaft 2 there is

- 10 mounted the type-wheel 14. Thus the type wheel and the selector arm are in fixed relation one to the other and move together. In addition to the elements before referred to, the shaft 2 of one of the apparatus is 15 provided at a position between the frame members with a rigidly mounted arm 10 adapted to contact with the free end of an arm 11 pivotally mounted upon the frame member 7 and acting as an armature to an 20 electro-magnet 13. Such elements comprise the synchronizing mechanism, the purpose and operation of which will be hereinafter described.

The distributor 9, Figs. 2 and 4, of each apparatus comprises four annular contact heads, the outer of which for each distributor consists of a series of contact blocks 15, insulated from each other and corresponding in number to the number of letters or signs provided upon the type wheel, for instance, twenty-eight, and each being connected by a lead with a transmitting key 29. The second contact head comprises a similar series of contact blocks 16, but narrower in width than the contact blocks 15. The corresponding blocks 15 and 16 are connected by flexible connecting leads. The third contact head comprises a series of contact blocks 17 identical with the blocks 16 of the second contact head but electrically connected together, for example, by integral formation with an interrupted annular member after the manner of the teeth of a comb. The fourth contact head 28 is a complete metal ring. The construction of the distributor as hereinbefore described is the same for each apparatus. For the purpose of effecting the synchronizing operation, however, each distributor has certain additional elements which are different. The distributor of the apparatus whence the current effecting the synchronizing operation originates has included in the first contact head two additional insulated metallic blocks 23, 24 and a block of insulating material 24^a. The block 23 is in communication with the arm 25 of a two way switch, which has one contact stop 26 in connection with a source of electrical potential of suitable sign and the other contact stop 27 connected to earth. The block 24 is connected with a source of electrical potential of opposite sign to that with which the stop 26 is connected. The distributor of the apparatus provided with the synchronizing mechanism has in

cluded in the first contact head, in a position corresponding to that of the block 24 of the other distributor, a block 57, (Fig. 4), disposed between two blocks of insulating material, and in the third contact head an insulated block 58 in the same radial position as the block 57. The electrical connections of these blocks will be hereinafter described. 70

The selector arm 8 of each apparatus carries at its outer extremity a conducting brush 18 in such a position that in the revolution of the arm it contacts with the blocks 15 of the first contact head and the blocks 24 and 23 in the one distributor and the block 57 in the other distributor. The brush 18 is in electrical conducting connection with the axial point of the arm; for this purpose the arm is advantageously formed of metal. The selector arm also carries, by means of a bridge member 20, three brushes 19, 21, and 22 adapted to contact respectively with the second, third and fourth contact heads; and in the case of the brush 21, the block 58 of the one distributor. These three brushes are in electrical communication through the bridge 20 which is insulated from the selector arm by the insulation 20a. 75 80 85 90 95

The lever 31, Fig. 3, by whose oscillations 95 the several operations of the apparatus are effected, is pivotally mounted at 32 on the outer face of the frame member 7 in a position below the type wheel 14, over which is mounted and in contact therewith the inking roller 30. At its free end the lever 31 is formed as an escapement fork or double pawl 33 for engagement with a ratchet wheel 34 secured to the spindle of a roller 35 over which passes the strip 36 of paper or other material upon which the printing is to be effected. The strip is maintained in the necessary frictional contact with the roller by a resilient arm or presser 37. A bracket member 38 is mounted upon the lever 31 at 100 a position adjacent the pivotal point 32 and has pivoted to it a second but smaller lever 39 carrying at its free end an impression roller 40 over which the strip material passes. The lever 39 is capable of an oscillation limited on the one hand by the lever 31 and on the other hand by a stop 41 mounted on the lever 31. It is, however, maintained normally in the lower position 105 by the action of a spring 42 exerting a slight pressure upon it which may be regulated by an adjusting screw 43. A polarized electro-magnet 52 is mounted below the lever 31 which acts as an armature and is normally maintained in contact with the core of the electro-magnet in opposition to the action of a spring 53^a tending to draw it upwardly 110 against a stop 53 mounted on the frame 7. The lever 31 carries at its pivot three spring contact arms 44, 47 and 49, the arms 47 and 115 120 125 130

49 being insulated. The arm 44 according to its position makes contact with one or other of two contact screws 45 and 46. Similarly, the arm 47 contacts either with a contact screw or stop 48^a or with the contact screw 48 and the arm 49 either with the contact screw 50 or the contact screw 51. When the lever 31 rests upon the core of the electro-magnet 52, the arm 44 contacts with the screw 45, the arm 47 with the screw 48^a and the arm 49 with the screw 50, while when the lever 31 rests against the stop 53, the arm 44 contacts with the screw 46, the arm 47 with the screw 48 and the arm 49 with the screw 51.

The operation of this mechanism is as follows:—The type wheel 14 being rotated at a uniform speed by the prime mover, the moment the type to be impressed arrives 20 opposite the impression cylinder 40 the electro-magnet 52 is caused to relax its attraction upon the lever 31 which flies upward into contact with the stop 53 under the influence of the spring acting upon it. 25 This movement of the lever 31 serves instantly to throw the lever 39 upward to bring the strip material upon the impression cylinder 40 into contact with the type. This contact is instantaneous, the lever 39 30 at once returning to its normal position under the action of the spring 42, so that though the type wheel 14 is not arrested for the impression, a clear impression is secured. Immediately the impression has 35 been effected the electro-magnet 52 is caused again to attract the lever 31 to the initial position, by which movement the escapement fork 33 rotates the wheel 34 through one tooth, feeding the strip material forward the necessary distance to 40 permit a fresh impression to be made.

The necessity for synchronizing the instruments at the two ends of the line will be appreciated when it is remembered that 45 the two type wheels are rotated by independent and constantly running prime movers. Should the speeds at which the two type wheels are rotated differ in the least degree, the accurate transmission of messages would become impossible after a short time. It is the purpose of the synchronizing mechanism to meet this difficulty, by automatically arresting the movement of one of the type wheel mechanisms at 50 a certain point in the rotation when want of synchronism exists and retaining the mechanism arrested until the two type wheels are in synchronism. This can be effected as often as once in every rotation of the type 55 wheels, should the conditions be such as to require this. So long as synchronism exists, however, the synchronizing mechanism acts in such manner as to offer no obstruction to the free movement of the type wheel 60 mechanism.

The electrical connections and devices required for the transmission and reception of messages by means of the apparatus are described with special reference to Fig. 4 as follows:—

Each transmitting key 29 is connected with a block 15 of the first contact head of the distributor. Each key is provided with an arm 54 operating between two contacts 55 and 56². The arm 54 is normally in contact with the contact 55. The contact 56² is connected with a source of positive potential. The axial point of the selector arm 8 is connected to the contact screw 45. As shown in Fig. 4, however, this line includes 70 a two way switch 60² under the control of an electro-magnet 62, being connected to the contact 59². The other contact 63 of the switch 60² is connected to a hand-operated two-way switch 65 adapted to connect the 75 line either to earth or with a source of negative potential. The switches 60² and 65 are not necessary to the transmission and reception of messages but are required in the case of the apparatus provided with the synchronizing mechanism as will hereinafter be explained. The contact screw 46 is connected to a hand-operated two-way switch 53 operating in connection with contacts 54², connected to earth, and 55², connected 80 with a source of negative potential. This switch is required for discharging the line quickly. Where the line is of short length it suffices for it to be earthed but in the case where it is of extensive length it is advantageous to employ the source of negative potential.

The third contact head is connected to the contact screw 50 while the contact screw 51 is connected with a source of negative potential. The arm 49 of the lever 31 is connected to one terminal of the coil of the electro-magnet 52, the other terminal of which is connected to earth. In order to avoid 95 sparking on the breaking of the circuit of the electro-magnet 52, the coil is advantageously short-circuited through a condenser 80.

In addition to the foregoing connections, for the reception of messages the following 100 connections are also made:—

The contact 55 of the transmitter key arm 54 is connected with the coil 56 of a polarized relay and thence to a contact 57² of a two-way switch 58² under the control of 105 the electro-magnet 62 and through the switch to earth. A dead contact 64 is provided for the switch 58² when not attracted by the electro-magnet 62. The armature switch 59 of the polarized relay is connected 110 to earth, and operates between contacts 60 and 61. The switch normally rests against the contact 60 which is connected through the coil of the electro-magnet 62 with a source of positive potential. The contact 115 120 125 130

61 is connected with the negative terminal of a local battery 66, the positive terminal of which is connected with the fourth contact head 28. A second coil 68 of the polarized relay is connected through one terminal with the contact screw 48, the other terminal being connected to earth. The arm 47 of the lever 31 is connected with a source of positive potential.

- 10 In the apparatus provided with the synchronizing mechanism for the operation of this mechanism the block 57 is connected to the positive side of the coil 56 of the polarized relay, and the block 58 is connected through the coil of the electro-magnet 13 to earth. The armature 11 of this magnet, which is adapted to engage the arm 10 of the shaft 2, is connected with a source of positive potential and carries an arm 11^a which, in the lifted or attracted position of the armature 11, engages a contact 67 connected to the positive terminal of the other coil 68 of the polarized relay.

In considering the operation of the apparatus it is convenient to assume that the required transmitting key 29 of the apparatus, from which the message is to be transmitted, is depressed at a moment when the selector arm 8, rotating in a counter clock-wise direction, has not yet reached the block 24 or the block 57 as the case may be. If the selector arm 8 of the receiving apparatus with the synchronizing mechanism is in advance of the selector arm 8 of the transmitting apparatus, when it reaches the block 57 the arm 10 of the shaft 2 will be arrested by the arm 11 and the shaft 2 will be brought to rest, the driving member 1 continuing to rotate upon the shaft, and 40 sliding against the collar on the shaft under the action of the spring 3. When the selector arm 8 of the transmitting apparatus reaches the block 24 of the distributor and the selector arms are thus in identical positions, current passes from the battery 24¹ (Fig. 2) through 18, 8, 59², 60² to the screw contact 45 and arm 44 of the lever 31 to the line conductor 70. At the receiving apparatus the current passes through the line 70, 50 arm 44, screw contact 45, lead, and switch 60² to the selector arm 8 to the block 57 and thence to the relay coil 56 and the switch 58² to earth. The relay will thus cause the armature 59 to swing over, breaking the circuit of the electro-magnet 62 so that the switches 58² and 60² pass respectively to the contacts 64 and 63, breaking the circuit of the relay coil 56 and connecting the line conductor to earth or a source of 60 negative potential through the switch 65, for the discharge of the line conductor. When the armature 59 swings over to the contact 61 the circuit of the battery 66 is completed through the fourth contact head 28, the brushes 22, 21, the block 58, the coil

of the magnet 13 to earth. The armature 11 is thus lifted to release the arm 10 so that the selector arm 8 is again driven, by the action of the driving member 1, and in synchronism with the selector arm of the other apparatus. The movement of the arm 11 closes the circuit through the contact 67 to the coil 68 of the relay to earth. The armature 59 is thus at once oscillated back into contact with the contact 60 to reinstate the original connections. In the meantime at the other apparatus the selector arm 8 will have passed to the block 23 whereby the line conductor will be connected to earth or to the source of negative potential for the discharge of the line conductor. When the selector arm 8 of the transmitting apparatus reaches the block 15 corresponding to the depressed transmitting key 29, a current passes from the contact 56² to the block 15 and thence by way of the selector arm 8 as before to the conductor line. At the far end it follows the same course as before from the arm 44 to the selector arm 8, and thence through the block 15 to the transmitting key 29 corresponding to that of the depressed key of the transmitting apparatus. It then passes by way of the arm 54 and contact 55 to the relay coil 56 and thence to earth. The relay armature 59 is thus operated as before to 95 cut the circuit of the electro-magnet 62 and to close the local battery circuit. Current from the battery 66 then passes by way of the fourth contact head 28, and the brushes 22 and 21 to the contact head 17 and thus to the contact screw 50 and by way of the arm 49 to the coil of the polarized electro-magnet 52 and to earth. The electro-magnet 52 releases the lever 31 which flies upward for the impression of the type on the strip material passing over the impression roller 40. 100

In effecting the upward movement the lever 31 throws the arm 44 into contact with the screw-contact 46, the arm 47 into contact with the screw-contact 48, and the arm 49 into contact with the screw-contact 51. As the result the arm 44 puts the line into connection with the switch 53 for the discharge of the line conductor, the arm 47 closes the circuit through the contact 48 and the coil 68 of the relay for the return of the armature 59 to its initial position and the arm 49 connects the coil of the electro-magnet 52 through the screw-contact 51 with the 115 source of negative potential for the purpose of causing it again to attract the lever 31 into the original position, in making which movement the lever 31 feeds the strip material forward as hereinbefore explained. 120

Simultaneously at the transmitting apparatus the selector arm 8 moving slightly forward brings the brush 19 into contact with the block 16 of the second contact head corresponding to the live block 15. As these 125

- blocks are electrically connected the block 16 is at the same potential as the block 15 and current accordingly flows by way of the brush 19 and the brush 21 to the block 17 of the third contact head and thence to the screw-contact 50, the arm 49 and the electro-magnet 52 to earth. The lever 31 is therefore released and an impression of the letter or sign transmitted is thus made simultaneously at the transmitting station and serves for the purpose of verification and checking. The movement of the lever 31 serves to discharge the line conductor by connecting it with the switch 53 and serves to connect the 15 coil of the electro-magnet 52 with the source of negative potential through the screw contact 51 for the purpose of causing the electro-magnet to return the lever 31 to its initial position.
- 20 The purpose of mounting the second and third contact heads so that they may be displaced relatively to the first contact head is to allow for the retardation due to the electrical inertia or the electro-static charging and 25 self-induction of the line conductor which will vary according to the conditions of each particular line.

The rapidity with which the lever 31 is operated permits the line conductor to be discharged during the time that the selector arm takes to pass from one block to another of the distributor, the operation of the apparatus being sufficiently rapid to allow as many as fourteen signals to be transmitted 35 or received during one revolution of the type wheel.

It will be understood that the invention is not limited to the use of the electrical connections and devices precisely as hereinbefore described as it is clear that these may be varied without departing from the invention.

I claim:—

1. A telegraphic printing apparatus serving for the transmission and reception of messages for signals, comprising a lever and means coöperating therewith for effecting its oscillation to effect the printing impression, the forward end intermittent feed of the strip material upon which the impression is made and the discharge of the line conductor after the transmission of each sign or letter, substantially as described.

2. A telegraphic printing apparatus serving for the transmission and reception of messages or signals, comprising a lever formed as the armature of an electro-magnet, said lever having a number of contact arms one of which serves for discharging the line conductor after each transmission of a sign or letter, a spring under the action of which said lever is constantly subjected and an electro-magnet adapted to attract the said lever in a direction contrary to the action 60 of the said spring, substantially as described.

3. A telegraphic printing apparatus serving for the transmission and reception of messages or signals, comprising a spring operated lever formed as the armature of an electro-magnet having a number of contact arms one of which serves for discharging the line conductor after each transmission of a sign or letter, a second lever mounted upon the first and adapted to carry an impression roller for effecting the printing impression and the forward end intermittent feed of the strip material upon which the impression is made, substantially as described.

4. A telegraphic printing apparatus serving for the transmission and reception of messages or signals, comprising a spring operated lever formed as the armature of an electro-magnet, said lever having a number of contact arms one of which serves for discharging the line conductor after each transmission of a sign or letter, a second spring-operated lever mounted upon the first referred to and carrying an impression roller for effecting the printing impression and the forward end intermittent feed of the strip material upon which the impression is made and a spring under the action of which the second lever referred to lies, substantially as described.

5. A telegraphic printing apparatus serving for the transmission and reception of messages or signals, comprising a lever formed as the armature of an electro-magnet, said lever having a number of contact arms one of which serves for discharging the line conductor after each transmission of a sign or letter, a spring under the action of which said lever is constantly subjected and an electro-magnet adapted to attract the said lever in a direction contrary to the action of the said spring, and means for the adjustment of the tension of said spring, substantially as described.

6. A telegraphic printing apparatus serving for the transmission and reception of messages or signals, comprising a lever formed as the armature of an electro-magnet, said lever having a number of contact arms one of which serves for discharging the line conductor after each transmission of a sign or letter, a spring under the action of which said lever is constantly subjected, an electro-magnet adapted to attract the said lever in a direction contrary to the action of the said spring, and means to effect impressions of the letter or sign transmitted at the transmitting and receiving stations simultaneously notwithstanding the retardation due to electro-static charging and the self-induction of the line, substantially as described.

7. A telegraphic printing apparatus serving for the transmission and reception of messages for signals, comprising a lever

formed as the armature of an electro-magnet, said lever having a number of contact arms one of which serves for discharging the line conductor after each transmission of a sign or letter, a spring under the action of which said lever is constantly subjected, an electro-magnet adapted to attract the said lever in a direction contrary to

the action of the said spring, and means whereby the mechanisms of the transmitting and receiving apparatus are synchronized automatically, substantially as described.
